Henry S. Carlson, West Orange, N. J., assignor to
 Thomas A. Edison, Incorporated, West Orange,
 N. J., a corporation of New Jersey

Application October 30, 1937, Serial No. 171,819

7 Claims. (Cl. 312—23)

This invention relates to improvements in cabinets. Although no unnecessary limitation thereto is intended, the invention has particular utility, and is illustrated and described, in connection with cabinets for such instruments as phonographs of the commercial type.

It is highly desirable that phonograph cabinets have a pleasing appearance, and particularly in commercial phonographs, it is very important that the cabinet be so designed as to make the phonograph conveniently operable.

It is an object of my invention to provide such improvements in cabinets for commercial phonographs as will permit greater convenience in the operation of the phonograph.

It is another object to provide a pivotal support for the phonograph so that the phonograph may swing downwardly upon the closing of the cover and thereby permit the overall height of the cabinet to be reduced.

It is another object to provide, in a phonograph cabinet of reduced overall height, means operated by the cover for making the phonograph conveniently accessible as the cover is moved to its open position.

It is another object to provide general improvements in cabinets for commercial phonographs so that the cabinet may be designed with a more pleasing appearance.

Other and allied objects will more fully appear in the following description and the appended claims.

In the description of my invention reference is had to the accompanying drawings, of which:

Figure 1 is a partial, vertical, sectional view of a phonograph cabinet showing the cover in closed position and showing in side elevation a phonograph and support mechanism therefor as provided within the cabinet.

Figure 2 is a view generally similar to Figure 1, showing the cover of the cabinet in open position and the phonograph in an upper or operative position;

Figure 2a is a detailed sectional view of a portion of the phonograph support mechanism as taken along the line 2a—2a of Figure 2;

Figure 3 is a front view taken along the line 3—3 of Figure 2;

Figure 4 is a fractional, horizontal view, partly in section, showing the lower main portion of the phonograph cabinet, and of the phonograph when in operative position; and

Figure 5 is a detailed view of a portion of the phonograph support mechanism.

Reference being had to the figures, there will

be seen a cabinet A comprising a main portion or lower compartment 1 and an upper compartment 2, the two compartments being separated by a plate 3 pivotally secured to the cabinet about the pivoting axis 4. The plate 3 carries on its upper side parts of a phonograph B which comprises principally a rotatably mounted mandrel 5 carrying a record 6, a carriage 7 which supports a translating device 8, and a speaking tube 9 which is coupled to the translating device 8. The carriage 7 is slidably mounted so as to be moved longitudinally of the record 6 as the mandrel 5 rotates. Rotation of the mandrel 5 is usually effected by means of an electric motor mechanically connected thereto through an electrically operated clutch, the motor and clutch being not shown. On the far end of the speaking tube 9 is carried a handpiece 10 on which is mounted a manually operable switch 11 for controlling the operation of the aforementioned clutch, or any other mechanical action as may be desired. The motor receives its electric power by way of the leads comprising the cable 12. This cable connects the female plug 13 to the male plug 14, the former serving to make connection to a source of electrical power and the latter to the motor. A pushbutton type of switch 15, connected in one of the leads of cable 12, is provided for breaking the circuit which connects the power supply to the motor. This switch is mounted on a bracket 16 and is adapted to be operated to a circuit breaking position whenever the handpiece 10 is placed in its holder 17 (see Figure 3) by the engagement of the end portion 10' of the handpiece 10 with the button 15' of the switch 15. Thus, by placing the handpiece 10 in its holder 17, as during periods of non-use, the motor circuit is automatically broken to stop the rotation of the motor.

At the front of the cabinet there is customarily provided a door 18 having a knob or handle 18' which swings forwardly about the pivot 19 to expose the interior of the lower compartment, or main portion 1. Along the inside of the door 18 there is commonly provided a container 20 for documents, folders, &c. Secured to the lower inner side of the container 20, as by the screws 21, is a rack 22 for holding record cartons such as 23. Upon opening the door 18 the container 20 and the cartons 23 become readily accessible.

At the top of the cabinet A there is provided a cover 24 which swings upwardly about the pivot 24' to expose the interior of the upper compartment 2; this upward swinging movement of the cover being to any convenient position such, for

example, as is illustrated in Figure 2. The cover 24 may very desirably have side fins 24" on each side thereof which project downwardly therefrom. These side fins may be suitably secured to 5 the cover as by welding. I prefer that the side fins be so shaped as to provide when the cover 24 is in open position, a lateral enclosure of those parts of the phonograph which need not be accessible. From such open position the cover 24 10 may swing downwardly until it abuts against a stop 25 to completely enclose the upper compartment 2. The stop 25 for the cover may very suitably be the upper edges of the side walls of the lower compartment 1. When the cover 24 15 rests in its closed position its side walls preferably form an upward extension of the respective side walls of the main portion 1. On the inside of the cover 24 there may be appropriately connected, as by the pivot 62, a plate 63 which swings 20 upwardly into the top portion of the cover as the cover is closed by reason of the engagement of the plate 63 with the top portion of the bracket 16. Upon opening the cover 24, the plate 63 swings downwardly about its pivot 62 until it 25 engages with stops 64 and 65 which may very suitably comprise brackets secured to the respective wide walls of the cover 24. When the plate 63 is in its lower position it provides with the cover 24 a compartment 66 which is suitable for 30 holding letters, documents, etc.

In order to reduce the overall height of the cabinet A, and thereby improve its general appearance, it is very desirable to use a shallow or low cover. In this case the phonograph B mounted on the plate 3 will extend into the path of the cover 24, and therefore it is necessary that the phonograph B be movable downwardly to permit the cover to close. The phonograph is 35 inoperative when it is in its downward position 40 and must therefore be restored to its upward position in order to be used again. However, I greatly facilitate the use of the phonograph by moving it downwardly and upwardly with the respective downward and upward movements of 45 the cover. For doing this there is provided a supporting mechanism for the phonograph B which is operated by the cover 24 to remove the phonograph B from the path of the cover 24 as the cover is moved downwardly to its closed position. 50 For restoring the phonograph to its operative position as the cover 24 is moved upwardly to its open position. It is with such means that my invention is primarily concerned, where- 55 fore the supporting mechanism is hereinafter described in detail.

For illustrating my invention the plate 3 on which is mounted the phonograph B has been shown as being swingingly movable about a pivoting axis 4 that is substantially in alignment 60 with the pivot 24' of the cover 24. It is to be understood, however, that the pivot for the phonograph support mechanism need not necessarily be in such substantial alignment with the cover pivot, as my invention contemplates, in its broader aspects, any downward swinging movement of the phonograph B as the cover 24 is moved downwardly to a closed position, or any converse upward swinging movement of the phonograph to an operative position as the cover is moved upwardly to its open position. The pivotal mounting for the phonograph is particularly desirable in that it permits a simple locking arrangement 65 operable by the cover for holding the phonograph in its operative position; moreover, such 70 pivotal mounting permits the use of simple 75

mechanical means, connected between the cover 24 and the plate 3, for moving the phonograph downwardly and upwardly with the respective downward and upward movements of the cover 24.

The plate 3 which carries the phonograph B may very suitably be a casting having a reinforcing rib 3' extending along each side of the plate and downwardly from the bottom thereof. The rib 3' is disposed a short distance in from 10 the edges of the plate 3, and very conveniently serves as a means for attaching the plate 3 to the framework of the supporting mechanism. On the top forward side of the plate 3 there is provided a groove 3" which serves to hold the intermediate portion of the speaking tube 9 in 15 a suitable position when the handpiece 10 is placed in its holder 17.

The supporting mechanism for the phonograph comprises a pair of linkage systems, one of which 20 is disposed along each side of the cabinet. In numbering the components of these systems I use even numbers on the left hand side and odd numbers on the right. In these linkage systems there are, extending the full length of each side of the 25 plate 3, the supporting members 26 and 27 which are respectively pivotally connected to a pair of studs 28 and 29 to form the pivoting axis 4. These studs 28 and 29 are carried by the respective brackets 30 and 31 which are secured to the 30 upper portion of the rear wall of compartment 1, on opposite sides thereof, by suitable means such as by rivets or by welding. The members 26 and 27 extend along the side portions of the reinforcing rib 3' and underneath the side edges of 35 the plate 3, thereby supporting the plate and phonograph B. For holding the plate in proper mechanical relation to the supporting members 26 and 27 there are provided a pair of pins 32 and 33, one on each side of the plate 3, which 40 respectively register with the notches 26' and 27' of the respective members 26 and 27. By this arrangement it is obvious that the plate 3 is 45 gravitationally held against the supporting members 26 and 27, and may therefore be lifted upwardly from its supporting framework to make readily accessible, for servicing or repair, any parts or mechanism located underneath the plate.

Pivots connected to the respective members 26 and 27, as by pivots 34' and 35', are link 50 members 34 and 35. These members are respectively pivotally connected at their lower ends to a pair of levers 36 and 37, this connection being made by suitable pivots such as by the pivot 37' for connecting 35 to 37. The levers 36 and 37 55 are hinged to the respective brackets 38 and 39 which are secured to the rear wall of compartment 1, as by rivets or by welding. At a short 60 distance from the ends of the levers 36 and 37 there are respectively provided pins, such as pin 41 for the lever 37, which pins respectively engage with longitudinal slots provided in a pair of actuating links 42 and 43, such as the slot 41' in the link 43. These actuating links 42 and 43 65 are respectively hinged to the cover 24, about the studs 44 and 45, to couple the cover with the supporting mechanism of the phonograph. By 70 this means the plate 3, supported by the members 26 and 27, will swing downwardly within the lower compartment 1 as the cover is moved downwardly, and conversely it will swing upwardly as the cover is moved upwardly. The location of the pivots and the length of the various 75 members comprising the linkage system are adjusted so that the plate 3 will rest in a horizontal 80

position when the cover is located in its open position, sufficient downward movement of the plate 3 being obtained to remove the phonograph from the path of the cover as the cover is moved downwardly to its closed position.

The supporting members 26 and 27 have their front portions 26'' and 27'' bent outwardly at right angles, this bend being made along a line that is disposed at an angle somewhat greater than 90° with the lower longitudinal edges of the respective members. Located in the front portion of compartment 1, and substantially directly underneath the respective bent portions 26'' and 27'' are the respective levers 46 and 47 which pivot about the respective studs 48 and 49, these studs being carried by the respective brackets 48' and 49'. These brackets are rigidly secured to the respective side walls of compartment 1, as by rivets or by welding. The levers 46 and 47 have respective upper end portions 46' and 47' which are bent inwardly at right angles, which portions 46' and 47' are adapted to engage the underside of the respective portions 26'' and 27'' to lock the supporting members 26 and 27 in their horizontal positions. The levers 46 and 47 are spring biased in a counter-clockwise direction, as by the spring 51 for the member 47, and are positioned so as to be respectively engaged by the lower end portions 42' and 43' of the actuating links 42 and 43, which portions 42' and 43' are bent outwardly at right angles as shown. By such engagement the cover 24 is yieldably held in its open position (as shown in Figure 2) in which case the pins 40 and 41 contact the lower end portions of the respective slots 40' and 41'. As the cover is moved downwardly from such open position, the actuating links 42 and 43 may move downwardly through the length of the respective slots 40' and 41' without moving the supporting members 26 and 27 downwardly; however, the end portions 42' and 43' of the actuating links 42 and 43 engage the respective levers 46 and 47 to move them in a clockwise direction, and thereby move their respective end portions 46' and 47' out from under the end portions 26'' and 27'' to permit the supporting members to move downwardly with the downward movement of the cover. The weight of the phonograph will tend to move the supporting mechanism and cover downwardly with considerable force, and for counteracting this effect heavy springs 52 and 53 are disposed between the respective pins 40 and 41 and the lugs 54 and 55 suitably located on the rear wall of compartment 1. In the upward movement of the cover the pins 40 and 41 respectively register with the lower end portions of the slots 40' and 41' to move the supporting members 26 and 27 upwardly about their respective pivots. In the upward movement of the supporting members 26 and 27 their forward bent portions 26'' and 27'' move up in front of the bent portions 46' and 47' and contact therewith. By reason of the angular position of the portions 26'' and 27'' further upward swinging movement of the members 26 and 27 cause the lever arms 46 and 47 to be moved in a clockwise direction. After the portions 26'' and 27'' have moved above the portions 46' and 47' the levers 46 and 47 snap back in a counterclockwise direction, as by reason of the spring 51 for the lever 47, to lock the supporting members 26 and 27 in their horizontal position and to resiliently hold the cover 24 in its open position.

The actuating links 42 and 43 may be disconnected from the cover 24 to permit the cover to

be swung upwardly to any desired position so that the phonograph may be lifted from its supporting mechanism, as for servicing or repairs. The detachable coupling of the actuating link 43 to the cover may, for example, be suitably effected by the means illustrated in Figure 2a, it being understood that the actuating link 42 on the lefthand side is similarly coupled to the cover. A bracket 57 secured to the cover, as by rivets or by welding, carries the stud 45 which may be suitably held as by a pressed fit. The link 43 pivots about the stud and is removably held thereon by means of a locking member 59 pivotally secured to the link 43, as by pivot 59', and having a notch which engages an annular groove 45' 15 provided near the end of the stud 45. The locking member 59 extends beyond the link 43 so that it may be manually disengaged from the groove 45' to permit the link 43 to be removed from the stud 45. 20

To facilitate the accessibility of the parts carried under the plate 3 there is provided means whereby the plate 3 may be swung upwardly from its supporting members 26 and 27 about the pivoting axis 4. Such means comprise the arms 60 and 61, one of which is secured to each side of the plate 3 as by the screws 60' and 61', respectively. These arms extend rearwardly of the plate 3 and have near their backward ends on the bottom sides thereof the respective notches 30 60'' and 61'' which are adapted to engage the respective studs 28 and 29.

I have disclosed my invention herein in terms of a specific embodiment, but it is to be understood that this embodiment is merely illustrative of my invention and not limitative thereof. My invention may be modified and may be embodied in other forms, which will not necessarily constitute a departure from the true scope thereof, and which I now undertake to express according to the following claims.

I claim:

1. In a cabinet having upper and lower compartments and a cover for said upper compartment pivoted to move upwardly to an open position and downwardly to a closed position: a pivotally mounted plate separating said compartments and adapted to carry an instrument; means, connecting said cover to said plate, for swinging said plate upwardly as said cover moves through the greater portion of its upward travel and for causing said plate to be swung downwardly as said cover moves through the greater portion of its downward travel; and means operated incidental to the act of moving said cover through the last portion of its upward travel for locking said plate against downward movement, and through the first portion of its downward travel for unlocking said plate.

2. In a cabinet having a compartment for an instrument: a cover pivoted to move upwardly to an open position; a downwardly movable plate defining the bottom of said compartment and adapted to be locked in an upper position; means operated as an incident of moving said cover through the last portion of its upward travel and through the initial portion of its downward travel for respectively locking and unlocking said plate; and means for yieldably holding said cover in said upper position while said plate is locked.

3. In a cabinet having a compartment for an instrument: a cover for said compartment pivoted to move from an open position to a downward position to close the same; a plate defining

- the bottom of said compartment and swingingly movable downwardly; means for locking said plate against said downward movement; and means operated incidental to a downward movement of said cover through the first portion of its travel to render said locking means ineffective, and through the remaining portion of its travel to cause said plate to be swung downwardly.
5. In a cabinet having a main portion and a cover pivoted to move upwardly and downwardly: a support disposed near the top of said main portion and pivoted thereto; means, connected between said support and said cover, for causing said support to be moved downwardly and upwardly with the respective downward and upward movements of said cover; means movable under said support to lock the support against downward movement; means for moving said locking means into locking position as said cover is moved through the end portion of its upward travel; and means, operated by said cover, for moving said locking means out of locking position as said cover is moved downwardly.
10. In a cabinet having a main portion and a cover pivoted to move upwardly and downwardly: a support disposed near the top of said main portion and pivoted thereto; means, connected between said support and said cover, for causing said support to be moved downwardly and upwardly with the respective downward and upward movements of said cover; means movable under said support to lock the support against downward movement; means for moving said locking means into locking position as said cover is moved through the end portion of its upward travel; and means, operated by said cover, for moving said locking means out of locking position as said cover is moved downwardly.
15. In a cabinet having a main portion and a cover pivoted to move upwardly and downwardly: a support disposed near the top of said main portion and pivoted thereto; means, connected between said support and said cover, for causing said support to be moved downwardly and upwardly with the respective downward and upward movements of said cover; means movable under said support to lock the support against downward movement; means for moving said locking means into locking position as said cover is moved through the end portion of its upward travel; and means, operated by said cover, for moving said locking means out of locking position as said cover is moved downwardly.
20. In a cabinet having a main portion and a cover pivoted to move upwardly and downwardly: a support disposed near the top of said main portion and pivoted thereto; means, connected between said support and said cover, for causing said support to be moved downwardly and upwardly with the respective downward and upward movements of said cover; means movable under said support to lock the support against downward movement; means for moving said locking means into locking position as said cover is moved through the end portion of its upward travel; and means, operated by said cover, for moving said locking means out of locking position as said cover is moved downwardly.
25. In a cabinet having a compartment for an instrument: a cover for opening and closing said compartment; a pivotally mounted support adapted to carry an instrument in said compartment; means, coupling said support with said cover, for causing said support to be moved upwardly and downwardly with the opening and closing of said cover; means for locking said sup-

port against downward movement; and resilient means, rendered effective upon opening said cover, for rendering said locking means operative and for yieldably holding said cover in open position.

6. In a cabinet having a compartment for an instrument: a pivotally mounted cover for said compartment; a movable support adapted to carry an instrument in said compartment; means for causing said support to be raised and lowered as said cover is opened and closed; means for locking said support against downward movement, rendered operative and inoperative incidental to the opening and closing of said cover; and means rendered effective as an incident to opening said cover, for yieldably holding said cover open.

7. In a cabinet having a compartment for an instrument: a cover for opening and closing said compartment; a movable support adapted to carry an instrument in said compartment; means for causing said support to be raised and lowered as said cover is opened and closed; means for holding said support in a raised position, rendered operative and inoperative as said cover is respectively moved through the end portion of its upward travel and the initial portion of its downward travel; and resilient means for yieldably holding said cover in the terminal position of said end portion of its travel.

HENRY S. CARLSON,
